UNIVERSAL ROLLING MILL

Wilhelm Büchels and Rudolf Heinrich Koppel,
Aachen, Germany, assignors to the firm
Rhein-Schelde Gesellschaft für Ingenieurwesen
m. b. H., Aachen, Germany

Application April 12, 1933, Serial No. 665,817
In Germany April 16, 1932

3 Claims. (Cl. 80—34)

Our invention relates to universal rolling mills, and more particularly to universal rolling mills which are equipped with means for actuating the individual rolls of the mill together.

5 It is an object of our invention to improve a universal rolling mill of this type.

To this end, we provide a driving shaft per roll which is operatively connected to the corresponding roll, arrange the driving shafts laterally with 10 respect to the axis of the mill and in parallel relation to the axis, and provide means such as a chain for actuating the driving shafts together.

As compared with the old rolling mills in which the individual rolls are actuated by a central 15 driving member, a mill according to our invention has the advantage of low initial cost. Another advantage of the decentralized drive by the laterally arranged driving shafts is that the speed of the individual rolls can be varied in a very simple manner, for instance, in the case of a chain 20 drive, by exchanging one set of sprockets for another set having a different number of teeth. A chain drive has the additional advantage that the depth of the housing is much reduced, with 25 a corresponding reduction in the overall length of a complete mill train. However, we are not limited to chain drive but may provide any other driving means, such as belts, ropes or cables or an internal gear, etc. By way of example, a chain 30 drive will be shown and described.

In a preferred embodiment of our invention, each individual roll, with its roll shaft and the corresponding driving shaft, is arranged in a casing which is adapted to be inserted in the housing 35 and to be adjusted by any suitable means, such as wedges or the like. When it is desired to remove a casing for inspection, repair or exchange, the driving means must first be detached, for instance, by separating the chain if such is 40 provided. The roll is then detached from the roll shaft and the casing can be extracted from the housing for repair, etc. It will appear that in this manner each casing can be removed, for instance, if trouble occurs, without disassembling 45 the complete housing, as is required in the old universal mills in which in such cases the corresponding housing is taken from the foundation and disassembled which often involves a lay-up of several days, so that it is usually preferred to 50 exchange a damaged housing for another housing while the damaged one is repaired.

In the housings according to our invention which make up a mill train, the axes of the individual rolls are arranged at such angles to horizontal that by turning one of the housings

through an angle of 180 degs. about its central vertical axis, the position of the axes in space, i. e., related to another casing which is still in its original position, is staggered with respect to their initial position. This has the advantage 5 that the roll axes in two housings can be staggered notwithstanding the fact that the housings themselves are quite similar. This is also important for manufacturing and shipping as the initial cost of the manufacture is reduced, fewer 10 spare parts are required and shipping is facilitated.

In the accompanying drawings, a universal mill embodying our invention, with three individual rolls in a housing, and a chain for driving the 15 rolls, is illustrated by way of example.

In the drawings

Fig. 1 is an elevation of the mill, with its housing partly in section on the axis of one of its three rolls,

Fig. 2 is a section on the line II—II in Fig. 1,

Fig. 3 shows one of the casings, viewed from the left in Fig. 2, and

Fig. 4 is a section on the line IV—IV in Fig. 3.

Referring now to the drawings, the housing 25 has a central casting or body 1, with a pair of end plates 2, 2 which are secured to opposite faces of the casting 1 by through bolts 23. The individual rolls 5, 5a and 5b, with their shafts 4, are mounted to rotate in casings 3. The casings 30 are divided in the axial plane of their roll shafts 4, each casing having a pair of flanged side plates 33 and 34, whose flanges are connected by screw bolts 37 and two bearings 46 and 47 with thrust rings 45. Bearings for the driving shafts 9, 9a 35 and 9b of the rolls 5, 5a and 5b are arranged at the outer ends of the casings and held by screw bolts 38 in the extended end portions 35 of the casings.

The rolls are held by nuts 6 on the inner ends 40 of their shafts 4, and driven by a bevel gear 7 at the outer end of the corresponding shaft 4 with which meshes a bevel gear 8 on the driving shaft 9, 9a or 9b. The driving shafts are not arranged centrally but laterally with respect to the axis A 45 of the mill, and extend in parallel relation to the axis. Rotation is imparted to the driving shafts from a main driving shaft 14, with a sprocket 13, sprockets 10 on the individual driving shafts 9, 9a and 9b, and a chain 11. Guides for the 50 chain are shown at 12.

The axes of all roll shafts 4 are arranged in a single plane in the example illustrated. A housing whose shafts are arranged in this manner, may be used for a complete mill train, i. e., the 55

5   housings for the mill train may be identical and the roll axes are staggered by turning one of the 10   housings through 180 degs. with respect to the adjacent housing, about its central vertical axis. 5   This axis is the unbroken portion of the section line II—II in Fig. 1. When the housing 1, 2 is 15   turned anti-clockwise through 180 degs. from the position in Fig. 1, the shaft 9 moves into the position of the shaft 9a in Fig. 1 and the other 20   shafts perform corresponding displacements in space, so that the shafts 4 of the individual rolls are staggered.

15   For adjusting the casings transversely to the roll shafts 4, we provide wedges 15 which are inserted in suitable grooves of the casting 1 with their parallel backs, and with their inclined faces bear on corresponding faces at opposite sides of the casings, as best seen in Fig. 1. Bolts 16 are attached to the wedges at their outer ends and 20   extend through bores 18 of the casing, and 17 are nuts on the ends of the bolts which project from the outer end of the extended portion 35. By rotating the nuts, the bolts 16 are shifted and the wedges 15 are displaced, effecting a corresponding 25   displacement of the casing 3. The small amount of transverse displacement which is possible with this wedge system, is amply sufficient for placing the rolls in the proper position with respect to the work.

30   30   For holding the casings 3 in their recesses in the casting 1, we provide screw bolts 20 in bores 19 of the casings which bores extend in parallel to the bores 18 for the bolts 16. The screw bolts 20 are anchored in the casting 1 at their inner 35   ends and equipped with nuts on their outer ends at 21 which bear on the outer ends of the extensions 35. The position of the bores 18 and 19 is best seen in Fig. 4. Detachable caps 22 protect the outer ends of the casings and the parts 40   projecting therefrom.

40   40   For extracting a casing, the corresponding cap 22 and the nuts 21 are removed and the wedges 15 retracted by the nuts 17. The chain 11 is separated which is done without any difficulty, and the casing can now be extracted for any purpose, for instance, repairing the bevel gears 1, 8. The driving shafts, 9, 9a and 9b also come out with the corresponding casings and the sprockets 10 are accessible.

50   50   The overall mechanical efficiency of the mill is very high as it has few members whose individual mechanical efficiency is also high. As mentioned, chain drive is particularly favorable as it reduces the depth of the housings. The individual housings of a mill train can be placed in close vicinity to each other so that the overall length of the train is short in proportion to the number of housings it comprises.

60   60   Instead of arranging all sets of rolls in a housing in a single plane as illustrated, the rolls might be arranged with the axes of their shafts 4 in two or more planes, as indicated in Fig. 2 where $a-b$ is the plane in which the axes of one set are disposed, and $a'-b'$ is the plane of the other

set. If two or more sets, with the axes of their shafts in several planes, are provided, they may all be driven by a single chain or the like, but obviously the housings with their sets in several planes are no longer quite similar.

5   We claim:

1. In a rolling mill, in combination, a plurality of angularly disposed spindles disposed with their axes in a common plane, rolls mounted upon said spindles and relatively positioned to mutually 10   coact in reducing in external diameter a tube or the like moving along a path normal to the plane of the spindle axes, a relatively narrow housing upon which the said spindles are rotatably mounted, the plane of the roll axes being 15   intermediate the substantially parallel planes of the side wall surfaces of the housing, a power transmission element having a portion intermediate the planes of the side wall surfaces of the housing, and means also intermediate the planes 20   of said surfaces for operatively connecting the power transmission element and the several spindles, whereby the spindles may be simultaneously driven.

2. In a rolling mill, in combination, a plurality of angularly disposed spindles disposed with their axes in a common plane, rolls mounted upon said spindles and relatively positioned to mutually 25   coact in reducing in external diameter a tube or the like moving along a path normal to the plane 30   of the spindle axes, a relatively narrow housing upon which the said spindles are rotatably mounted, the plane of the roll axes being intermediate the substantially parallel planes of the side wall surfaces of the housing, a power transmission element having a portion intermediate the planes of the side wall surfaces of the housing, and an endless member disposed and movable 35   in a plane intermediate the planes of the side wall surfaces which operatively connects the power transmission element and the several spindles, whereby the spindles may be simultaneously driven.

3. In a rolling mill, in combination, a plurality of angularly disposed spindles disposed with their axes in a common plane, rolls mounted upon said spindles and relatively positioned to mutually 45   coact in reducing in external diameter a tube or the like moving along a path normal to the plane of the spindle axes, a relatively narrow housing 50   upon which the said spindles are rotatably mounted, the plane of the roll axes being intermediate the substantially parallel planes of the side wall surfaces of the housing, a power transmission element having a portion intermediate 55   the planes of the side wall surfaces of the housing, and an endless chain connecting the power transmission element and the several spindles whereby the spindles may be simultaneously driven, said chain being disposed and movable 60   along a closed path, in a plane intermediate the planes of the side wall surfaces.

WILHELM BÜCHELS.
